UNITED STATES PATENT OFFICE.

WILLIAM T. SMITH, OF PHILADELPHIA, PENNSYLVANIA.

DESIGN FOR WOVEN FABRIC.

SPECIFICATION forming part of Design No. 34,739, dated July 2, 1901.

Application filed June 6, 1901. Serial No. 63,475. Term of patent 7 years.

To all whom it may concern:

Be it known that I, WILLIAM T. SMITH, a citizen of the United States, residing in Philadelphia, Pennsylvania, have invented and produced a certain new and original Design for a Woven Fabric, of which the following is a specification.

My design is shown in the accompanying drawing, which represents sufficient of the pattern to illustrate the design, the remainder being simply a repetition of what is shown.

The design comprises two figures 1 and three figures 2. The figures 1 each have a central figure 3 on a field having a bordering-band 4 with a straight inner boundary and a zigzag or toothed outer boundary. Outside of this band 4 is a zigzag band 5, and beyond the latter a band 6, similar to the band 4—

that is to say, having a straight inner boundary and a zigzag outer boundary. The figures 2 are triangular, each having a bordering-band 7 with a straight outer boundary and a toothed or zigzag inner boundary.

Having thus described my invention, I claim and desire to secure by Letters Patent—

The design for a woven fabric, substantially as described and as shown in the accompanying drawing.

In testimony whereof I have signed my name to this specification in the presence of two subscribing witnesses.

WILLIAM T. SMITH.
